UNITED STATES PATENT OFFICE

GIOVANNI PEDRAZZO, OF BIELLA, ITALY

AUTOMATIC COMMUTATOR

Application filed August 21, 1928, Serial No. 387,475, and in Italy September 4, 1928. Renewed July 18, 1931.

The object of this invention is a device which permits obtaining an automatic operation of the controller in multiple power machines and the like, in accordance with the power that may be required from the machine under varying working conditions.

The device according to the invention consists substantially in a series of electromagnets which are arranged radially or in a spider-like manner with suitable angular distances between adjacent ones, and these electromagnets act on a central movable core which is keyed to the shaft of the controller. The current furnished to these electromagnets is automatically controlled by means of relays in combination with other well known devices or by means of new devices which will hereafter be described, these relays or other devices being placed under the control of the variation of the intensity of the electric current absorbed by the machine, and the electromagnets through exerting a purely magnetic action on the core which they surround, cause the core and thus also the shaft of the controller to be shifted angularly to obtain the desired automatic operation of the controller.

The core may be single or double; that is, it may be applied to one side only of the shaft or to both sides, and the number of the electromagnets may be equal to the number of the power outputs that may be obtained or be smaller than such number. For example one electromagnet may be provided for each two power outputs, in which case the commutation is obtained, for example with a double core, by using the core on one side of the shaft for the lower outputs and causing the core on the other side to enter into action in order to continue the rotation of the shaft of the controller for the higher outputs.

The movable single core, or the double core which is used when the number of the electromagnets is smaller than the number of the obtainable output values, ends in a cylindrical surface and covers in any one of its positions of insertion of the various powers not only the respective electromagnet, but also a small portion of the neighbouring electromagnet or electromagnets towards which

it must be shifted, for the evident purpose of increasing the rotation couple from the neighbouring electromagnets when one of them is being fed in order to change the power.

A suitable retarding device is provided to prevent the electromagnets being fed for momentary variations of the load, as they are intended to be fed only as a result of persistent variations.

The invention will be described with reference to the accompanying drawings which show by way of example several exemplifications of my invention. In the drawings

a sudden passage from the maximum to the minimum power, and vice versa.

As shown in Figs. 1 to 3, the shaft *e* of the controller has keyed to it a hub member *f* which carries a core *g* made of laminated iron and which is a single core in Fig. 1 and a double core in Fig. 2. This core is exposed to the purely magnetic action of a plurality of stationary electromagnets I, II, III, IV, V, VI, VII, VIII (Fig. 1) or I, II, III, IV (Fig. 2) which surround it, and is adapted to impart after the manner of a handle a well defined angular displacement to the said shaft, whereby the automatic operation of the controller is obtained. The controller is provided, preferably interiorly with a star-shaped cam having a number of angular recesses equal to that of the powers and provided with a lever having a roller, and with a spring so that when one half of a revolution has been completed the spring causes the segments of the controller to return into the normal position.

An arrangement for a machine having *n* output values is shown by way of example in Fig. 1 where the *n* electromagnets I, II, III . . . are arranged in a spider-like formation at equal angular distances

$$\frac{360}{n}$$

apart. In another arrangement the number of the electromagnets may be equal to

$$\frac{n}{2}.$$

The figure shows an arrangement for eight output values. The movable core *g* which terminates with a cylindrical surface, covers in each of the *n* positions the respective electromagnet and in addition, a short length of the two neighbouring electromagnets. The angle between two neighbouring electromagnets may be reduced in case the number *n* of the outlet values is small, so that the core will not be excessively large, and in this case the maximum angular displacement of the shaft *e* will be less.

When the number *n* of the output values is small, the arrangement shown in Fig. 2 may be used (controller for three values), wherein the electromagnets are also arranged at equal angular distances apart and a double core is used, the two parts of which work alternately. In this latter case the displacement of the shaft of the controller in passing from one value to the other is

$$\frac{360^\circ}{2n}$$

(60° in the figure). In this case the core on one side covers only one of the electromagnets and the core on the other side covers a portion of the electromagnets towards which the core is to be shifted.

The above described arrangements of the core and of the electromagnets ensure an automatic control without the insertion of a mechanical friction resistance, and therefore a reliable operation without the need of lubrication and supervision.

The following description of an automatic control device with relays as shown in Figs. 4, 5 and 6 is given only by way of example to explain the automatic working of the commutating device according to the invention, it being understood that the construction may be varied in many ways within the limits of the claims.

In the upper part of Fig. 4, the letter *L* and the numbers from 1 to 15 designate the theoretical scheme of a three-phase current machine capable of developing eight output values in accordance with the invention described in an earlier application for patent of the applicant.

This control device consists of a system of relays which are acted on by the variation of the intensity of the current absorbed by the various outputs. The primaries of four current reducers *a*, *b*, *c*, *d*, the secondaries of which provide current respectively to the circuits of four relays indicated IV—VIII, III—VII, II—VI and I—V, are inserted in series with four suitable circuits indicated *m*, *m'*, *m''*, *m'''*. For low outputs the current reducers *a*, *b*, *c*, *d* may be omitted and the circuits *m*, *m'*, *m''*, *m'''* may be made to pass directly through the said relay. The relay I—V which is fed by the current reducer *d*, connects with the intermediate electromagnets II, VI and IV, the second relay II—VI which is fed by the current reducer *c*, connects with the minimum electromagnets III, I and the electromagnets VII and V, the third relay which is fed by the current reducer *b*, connects with the electromagnets IV, II, VIII (maximum) and VI, while the fourth relay IV—VIII which is fed by the current reducer *a*, connects with the electromagnets V, III and VII.

The details of a relay are shown in Fig. 5, which shows that the action of the intensity of the current, which acts through a current coil *h* on a magnetic bar *i*, in combination with the action of a push-pull spring *j*, produces the displacement of a small lever *l* which by means of contact elements *l'*, *l''* may establish two different contacts, an upper one *o* when the current increases and a lower one *p* when the current diminishes. For this purpose the lever *l* engages with its free end a fork *q* carried by an extension of the magnetic bar *i*, this engagement being such that as the lever is acted on by a small spring (not shown) the contact in one or the other position will occur instantaneously. Each relay is provided with a retarding device *r* so that its action will not take place for merely in-

stantaneous and non-persisting variations of the load.

In order to avoid a strong pull on the spindle of the relay, the current coil enclosed within the magnet may be constructed with two internal cores of thin sheets of iron of which one is stationary and is traversed by the spindle while the other one is secured on the spindle. These two cores have their approaching ends, one in the shape of a point, and the other provided with a recess, and externally of the current coil is provided a sheath of wound sheet iron which carries covering pieces at its two ends. In this way the relay is transformed into a magnetic compensation relay.

Fig. 4 shows the revolving commutator keyed to the shaft e of the controller. The eight electromagnets I, II, III, IV, V, VI, VII and VIII are connected on the one hand with the contacts o and p of the relays, and on the other hand with eight metallic segments with which the central rotating core comes successively into contact. The supply to the electromagnets is obtained through the contacts of the relays from the secondary of a tension reducer t , the primary of which is inserted in shunt between two lines of the machine, or may also be connected directly, viz. without the tension reducer t , in case the tension is not very high. The feeding circuits of the electromagnets are shown with thin lines.

The central core of the commutator faces, in each of the eight positions, three successive segments, with the exception of the two extreme positions, in which it faces only two segments. For this purpose the first and the last segments are cut in such a way as to leave between them a sufficient space that when the core has arrived in one of its extreme positions, the core will not be attracted by the electromagnet which represents the other extreme position, and so that the movement of the controller will always take place by steps; this also prevents a simultaneous entrance of current into two coils of the electromagnets. Moreover, in order to avoid several electromagnets entering into action simultaneously, a mechanical arresting device is provided, as shown in Fig. 6. The four relays IV-VIII, III-VII, II-VI and I-V are arranged around the spindle of the controller at angular distances which are equal to those of the magnetic electromagnets I, II, III, IV, V, VI, VII and VIII (45° in the figure), and the displacements of their movable spindles i will or will not be possible according to the position of a cylindrical double-profiled cam s which is arranged concentrically respecting the shaft e of the controller. This arrangement will be described with reference to Fig. 7.

The sensitivity of the device is adjusted by means of the rheostats u , u' , u'' , u''' and

of slides v , v' , v'' , v''' . The slides z , z' , z'' , z''' together with a projection w on the rotating controller and with four contacts x , x' , x'' , x''' are used to short-circuit a portion of the said rheostats of the lower powers. All this will be more clearly described with reference to the scheme shown in Fig. 7.

In the upper part of Fig. 7 the letter L and the numbers from 1 to 12 indicate a theoretical scheme of a machine working on three phase current with six outputs (machine Pedrazzo). In this case the arrangement for the automatic control also consists in a system of relays acted on by the variation of the intensity of the current absorbed by the various outputs. The primaries of three current reducers a , b , c , are inserted in series with the three circuits of the machine, the secondary circuits of which reducers feed respectively the circuits of three relays which are numbered III-VI, II-V and I-IV. The relay I-IV which is fed by the reducer c , connects with the electromagnets II, V and VI (intermediate); the second relay II-V fed by the reducer b connects with the electromagnets III, VI (maximum), I (minimum) and IV; the third relay III-VI which is fed by the reducer a , connects with the intermediate electromagnets IV, II and V. The relays may be of the type illustrated in Fig. 5 or preferably of the type having a magnetic compensation, as above described.

The revolving commutator shown in Fig. 7 has a double core g and is fitted for the six outputs with the three electromagnets I-IV, II-V, III-VI which are arranged at an angle of 60° apart. The three electromagnets are fed through the contacts o , p of the relays from the secondary of a tension reducer t , as in Fig. 4, preferably with the addition of a condenser T' which serves to reduce sparking and the like. In each of the six positions of commutation the central core g covers with one or the other of its sides not only the respective electromagnet, but also a portion of the electromagnet towards which it must be attracted. The commutator is shown in the drawings by way of example in the position of the III value of output and with the core on this side covering a portion of the central electromagnet II-V in order to be made to pass into the II position when the intensity of the current absorbed by the machine continues to drop beneath a certain limit, and the contact p therefore is closed, while the core on the opposite side covers a portion of the electromagnet I-IV so that it can go over into the IV position when the intensity of the current increases beyond a certain limit, the contact o being closed in this case.

In order to prevent several electromagnets working simultaneously there is also provided

ed in this case a mechanical cam operated ar-
resting device as shown in Fig. 9.

The cam δ (Figs. 6 and 9) is provided with recesses which are diametrically opposite 5 each other in pairs, so that only the relay corresponding to the output which is inserted (third output in the drawings) is free to work, while the other relays are held in the middle position and are thus not working.

- 10 In this way, when the current is comprised between the maximum and minimum limit corresponding to a given output (III output value in the drawings) none of the electromagnets remains under tension, while only 15 one electromagnet at a time may enter into action and its insertion is instantaneous. The consumption of energy in the device therefore is quite small, because it is limited to the energy absorbed by the three current-respon- 20 sive circuits of the relays which are fed with a low tension.

The sensitivity of the device is adjusted in the following manner. With each of the current circuits is inserted in series a rheostat u' , 25 u'', u''' with slide v', v'', v''' for the desired regulation of the maximum and minimum value of the current which is to be assigned to each output value independently of the value assigned to the others; this is of the 30 greatest importance, more especially when in case of a large number of power-output values the limits of intensity between the successive values are somewhat vague and indefinite. It is further possible to assign a 35 different cut-out sensitivity to the various output values even during the working of the motor. This adjustment during the working of the motor may be easily carried through, especially if during the construction 40 due care has been taken to arrange the various rheostats in an easily accessible position.

Figs. 4 and 7 show an arrangement in which each relay is made to serve for two output values; they refer to a type of winding in which for the first outputs (of low values) the circuits are inserted in star connection and for the last (higher) outputs, in delta connection; in this way the same relay 45 may be used for a couple of values corresponding to the star-delta connection by merely varying the current of the relays in a given ratio. This is obtained by short-circuiting for the first values (star connected) 50 a portion of the resistance or rheostat u', u'', u''' inserted in the circuits of the relays, by means of a projection w placed on the revolving controller, the contacts x', x'', x''' , and a slide z', z'', z''' one of each of said 55 elements being provided for each of the said resistances, which may be adjusted for a perfect adjustment of the apparatus. The current at the projection w is carried by means of a brush f''' which slides on a conductor 60 ring f'' which is mounted on an insulating

supporting disc f' secured to the hub f of the core so that it may rotate therewith.

In order to prevent in the arrangement shown in Fig. 7 the commutator passing suddenly from the maximum to the minimum or from the minimum to the maximum power, viz. in order to prevent its being attracted so as to make a complete revolution, while it must make only five partial rotations of 60° in one or the other direction, but never the partial rotation of 60° between the extreme powers, a device may be used such as the one shown in Fig. 10. This device consists of a ring y which too is mounted by means of an insulator on the hub f of the core, and which is conducting throughout but a portion of its length, being interrupted by an insulating piece y' . The current which arrives from the reducer l is furnished to the electromagnets III—VI and I—IV through the said ring y and through a brush y'' . The ring is shown in Fig. 10 in the position which corresponds to the commutator being in the I output value. The current coming from the reducer l is interrupted at the electromagnet III—VI as the brush which conducts the current to this electromagnet bears on the insulating part of the ring y . A diminution of the intensity of current absorbed therefore has no influence on the rotating commutator. On the other hand, when the commutator is in the position corresponding to the VI output value, the insulating part y' of the ring y is in the position shown in dotted lines, and more precisely in front of another brush y'''' which therefore cannot carry current to the electromagnet I—IV, so that an increase of the intensity of current absorbed cannot produce a movement of the rotating commutator.

It is evident that when the number of the output values is different from the one shown and described, the number of the relays and of the electromagnets will also be different; the circuits however are quite similar to those shown in Fig. 4 or 7 and only the number of the various elements will be varied. It is also evident that a different arrangement may be used in both cases, besides the one shown in the examples described. The invention does not refer to the automatic arrangement for providing current to the electromagnets of the controller, which has only been shown and described by way of example. Besides, the automatic device which has been shown as having monophase electromagnets, may of course be constructed also for three-phase and polyphase current electromagnets which are fed by a suitable relay-interrupter attracted by the contacts o and p of the relays shown in Figs. 4 and 7, or by any other suitable arrangement of relays. Further, the invention is not limited to the use of the automatic device for machines with several powers, but also comprises the use of the device 130

for other purposes where it may be employed.

What I claim is:

1. An automatic commutation device for electric machines having a plurality of output values, comprising a series of substantially concentric electromagnets arranged in a spiderlike fashion at substantially equal angular distances from each other, a controller having a shaft, a movable central core on said shaft and on which the said electromagnets act, and means actuated as an incident to the variation in the intensity of the current absorbed by the machine, for selectively actuating the electromagnets, whereby the latter by their magnetic action on the core impart desired movement thereto, to produce selective angular displacement thereof and consequent automatic operation of the controller.
2. An automatic commutation device for electric machines having a plurality of output values, comprising a series of substantially concentric electromagnets arranged in a spider-like fashion, a controller having a shaft, a movable central core on said shaft and on which the said electromagnets act, means actuated as an incident to the variation in the intensity of the current absorbed by the machines, for selectively actuating only one of the electromagnets at a time, whereby the latter by its magnetic action on the core imparts desired movement thereto, to produce selective angular displacement thereof and consequent automatic operation of the controller, and means for automatically cutting off the current from the said electromagnet when the core is reaching its next angular position.

In testimony whereof I have signed my name to this specification.

40 GIOVANNI PEDRAZZO.
